UNITED STATES PATENT OFFICE.

EDWIN OLDFIELD AND PETER FLYNN, OF NORWICH, CONNECTICUT.

KINK-PREVENTER FOR SILK-SPINNING MACHINERY.

SPECIFICATION forming part of Letters Patent No. 487,334, dated December 6, 1892.

Application filed March 2, 1892. Serial No. 423,540. (No model.)

To all whom it may concern:

Be it known that we, EDWIN OLDFIELD and PETER FLYNN, both citizens of the United States, and residents of Norwich, in the county 5 of New London and State of Connecticut, have made certain new and useful Improvements in Kink-Preventers for Silk-Spinning Machinery, which improvements are fully set forth and described in the following specification, reference being had to the accompanying two sheets of drawings.

This invention relates to machinery for spinning or for doubling and twisting silk, and has for its object to prevent the kinking 15 of the fine strands of silk when the machine is stopped; and said invention consists in a simple device formed as a wire loop which may be brought into service at the proper time to hold the strand of silk taut.

20 Our invention further consists in mechanisms connecting said wire loops with the belt-shipping mechanism in such manner that the starting or stopping of the frame will serve automatically to bring into use or withdraw 25 the entire series of kink-preventers throughout the frame.

It is a commonly-known fact that when a silk-spinning frame is stopped—as, for example, at the close of the day's work or at the 30 noon-hour—such strands of silk as become slackened immediately double upon themselves and become badly kinked. Owing to these strands being very fine and easily broken, the operation of straightening out 35 such kinks becomes both a tiresome and expensive one. Frequently the strands are broken and have to be knotted, in which case the quality and value of the spun silk are materially lessened.

40 The drawings hereto annexed illustrate our invention, Figure 1 being a cross-sectional view of portions of a spinning-machine frame, showing in proper relation to each other the delivery-spool, the take-up bobbin, and such 45 other portions of the machine as are immediately connected with our invention. Fig. 2 is an enlarged perspective view of the belt-shipping rod, also one of our kink-preventing devices, and of the parts by means of which 50 action of the kink-preventers is effected when the shipper-rod is moved in either direction, as hereinafter explained in detail. Fig. 3

shows the driving-pulleys of the machine with portions of the belts coacting therewith, and also explains the manner of connecting 55 the shipper-rod with the principal of said belts. In Fig. 4 I have shown the shaft which carries the series of kink-preventers, and also a supplemental shaft or rod upon which said preventers rest when in service. Fig. 5 is a 60 front view, in elevation, of several of the delivery-spools with their spindles and the belt by means of which the series of spindles is rotated. This view also shows the kink-preventers in their elevated position—that is to 65 say, the position which they occupy during the operation of spinning.

In the drawings, the letter *a* denotes the delivery-bobbin suitably mounted upon spindles *b*, here shown as provided with a pulley *b'*, which is engaged and rotated at proper times by a belt *c*, which engages the rear side of the entire series of spindle-pulleys throughout the length of the machine, as perhaps best explained by Fig. 5. The spindles *b* are 75 journaled in the usual manner in the lower machine-rail *b*.

e denotes the usual take-up roll at the top of the machine; *e'*, a guide-eye, and *f* the strand of silk, the parts thus far described being the 80 same as in silk-spinning machines of ordinary construction.

Referring to Fig. 3, *g* denotes a vertical shaft bearing a loose pulley *g'* and fast pulley *g*² of equal diameters, which are engaged 85 and controlled by a main driving-belt *h*, and also a third pulley *g*³, fast on the shaft *g*, which last-named pulley carries the belt *c*, already referred to in connection with the spindle-pulleys.

h' denotes an angle lever fulcrumed at *h*² and having a loop or eye at the end of one of its arms through which the belt *h* passes, the free end of the other arm of said lever being connected with a long rod *h*³, extending the 95 length of the machine and by means of which the driving-belt may be shifted from the loose to the fast pulley, or vice versa.

Fig. 3 shows the driving-belt *h* on the loose pulley as it would appear when the machine 100 is at rest.

In the rear of the series of bobbins *a* (about at a level with the upper ends of said bobbins) is a shaft *i*, extending the length of the

machine, upon which is loosely mounted a series of angle-arms *k*, corresponding in number with the spindles of the frame, each angle-arm having secured to its horizontal portion a wire *k'*, which extends outward and terminates in a ring-shaped coil that is concentric with the upper end of the bobbin and at least a complete circle of which is in the same plane and touches the bobbin with which it coacts at all points when the wire is dropped upon said bobbin. The several angle-arms *k* may be prevented from lateral displacement upon the shaft *i* either by suitable collars secured to said shaft on either side of the angle-arms or by pins driven into said shaft, as shown in Fig. 2. Between shaft *i* and the line of bobbins is a supplemental shaft or rod *m*, which is supported by the free ends of arms *m'*, secured to the shaft *i* in such manner that when said shaft is partly rotated the arms *m'* and rod *m* are lifted correspondingly. The entire series of kink-preventers *k'* rest by gravity on the rod *m*, and it will be understood that when said rod is raised the kink-preventers are carried upward at the same time. Secured to shaft *i* is a rearwardly-projecting arm *i'*, having a slotted end which is entered by one arm of an angle-lever *n*, said lever being fulcrumed on a stud *n'*, secured to any convenient portion of the machine-frame. The free arm of lever *n* has secured to it a stud *n''*, which projects outward and across the shipper-rod *h*³ and lies between studs *h*⁴ *h*⁵, secured to said shipper-rod. When the shipper-rod is moved in the proper direction to stop the machine, the stud *h*⁴ engages the long stud *n''* of the angle-lever *n* and rocks said angle-lever on its fulcrum, and simultaneously the angle-lever imparts motion to the arm *i'*, which in turn rocks the shaft *i*, thus lowering the supplemental rod *m* and permitting the entire series of kink-preventers to drop by gravity upon the ends of spools *a*, as shown in Figs. 1 and 2 of the drawings. When, on the contrary, the shipper-rod *h*³ is moved in proper direction to start the machine into action, the stud *h*⁵ is brought into engagement with the long stud *n''* and the several connected parts are actuated to lift the entire series of wires *k'* a sufficient distance above the ends of the spools to permit the strand of silk to deliver freely from said spools. (See Fig. 5.)

We prefer to form angle-arms *k* and the supplemental rod *m* in such relation to each other that the kink-preventers may be raised and carried rearward to a point slightly past the vertical center of shaft *i*, as seen in dotted lines in Fig. 4, in which position they may be supported (out of the way of the attendant) at the time of starting up a frame or at any time when it is not considered necessary to use the preventers.

The kink-preventer wires are not formed as solid rings, but are so bent that their free ends are carried partially around within the

outer coil as if about to form a helix, a slight space being left between the inner and outer coils.

Our device operates as follows: When about to start a spinning-frame having our kink-preventers attached thereto, the entire series of preventers is thrown upward out of the way, bobbins *a* are placed on the several spindles *b*, and the silken strand from each of said bobbins is carried upward through the guide-eye and attached to the take-up spools *e*. The shipper-rod *h*³ is then moved longitudinally to shift the belt *h* onto the fast pulley *g*², and thus set in motion the pulley *g*³ and its belt *c*, when the last-named belt sets in revolution the series of spindles. When the shipper-rod has nearly reached the limit of its movement, (and after the spindles and bobbins are well speeded,) stud *h*⁵ engages the stud *n''* and rocks angle-lever *n*, which in turn rocks the shaft *i*, and the entire series of preventers is tilted forward until they are checked by rod *m*. It should be remembered that at this time the swiftly-whirling strands of silk are outside the wire preventers; but so soon as said preventers drop against the strands the latter are immediately whirled around through the open space between the overlapping inner and outer coils of wire until they pass within the practically-ring-shaped preventer, where they continue to whirl so long as the machine is in action. When it is desired to stop the machine, the shipper-rod *h*³ is moved to throw the main belt onto the loose pulley *g*¹, and as the spindles *b* slow down, the shaft *i* is rocked sufficiently to lower the rod *m*, and thus permit the preventer-rings to drop carefully upon the upper ends of the bobbins *a*, as the latter stop.

The wire rings are of somewhat less diameter than the bobbin-flanges with which they coact, so that when the rings are dropped upon the bobbins, they serve to bind the strands of silk upon the flanges of the bobbins and take up all slack, thus preventing said strands from doubling upon themselves and kinking.

When it is desired to again start the machine, it is only necessary to shift belt *h* onto the fast pulley *g*², when the mechanism described rocks shaft *i* to raise rod *m*, which latter carries upward with it the series of preventer-rings to positions, as shown in Fig. 5 of the drawings, in which positions the silk may render from the bobbins and whirl freely within the rings.

Having described our invention, we claim—

1. In a spinning-frame, the combination, with a series of spindles and delivery-bobbins, of a corresponding series of wire rings of less diameter than the bobbin-flanges and at least a complete circle of which is in the same plane, and adapted to touch the top surface of the bobbin at all points when resting thereon, whereby the threads may be clamped between the ring and the top of the bobbin, and mech-

anism for lowering said rings upon said flanges, substantially as and for the purpose specified.

2. The combination, with the delivery-bob-
bins, of a spinning-frame, a series of wire
rings of less diameter than the bobbin-flanges,
as herein set forth, at least a complete circle
of which is in the same plane and is adapted
to touch the top surface of the bobbin at all
points when resting thereon, whereby the
threads may be clamped between the ring
and the top of the bobbin, said rings being
formed helically and with an open space be-
tween the inner and outer coils, and means
for raising and lowering said rings relatively
to the bobbins, for the purpose specified.

3. In a spinning-frame, in combination with
the belt-shifting devices and the series of de-
livery-bobbins, a series of kink-preventers
consisting of wire rings of less diameter than
the bobbin-flanges with which they coact, at
least a complete circle of each of said rings
being in the same plane and adapted to touch
the top surface of the bobbin at all points
when resting thereon, whereby the threads
may be clamped between it and the top of the
bobbin, and mechanism intermediate the belt-
shifter and said preventer-rings for lowering

and elevating said rings, all being substan-
tially as and for the purpose specified.

4. In a spinning-frame, the combination,
with the belt-shifting mechanism provided
with stops, of a rock-shaft provided with a
rearwardly-projecting arm, a series of kink-
preventers secured to said shaft, an angle-le-
ver one end of which engages with the arm
of the shaft, and a stud secured to the other
arm of the lever, the front end of which is
adapted to be engaged by the stops upon the
belt-shifter, substantially as set forth.

5. In a spinning-frame, the combination,
with the belt-shifting mechanism, of a rock-
shaft adapted to be connected with and oper-
ated by the movement of the belt-shifter, for-
wardly-projecting arms rigidly secured to said
shaft, a rod in the outer ends of said arms,
and a series of kink-preventers loosely se-
cured upon said shaft and having their outer
portions resting upon and adapted to be raised
by the rod when the shaft is rotated upon its
axis, substantially as set forth.
